TORPEDO FIRING PISTOL

Joseph Marra and Marie M. Marra, Elkton, Md.,
now by judicial change of name Joseph Mars
and Marie M. Mars

Application July 1, 1932, Serial No. 620,474

1 Claim. (Cl. 42—54)

The present invention relates to a new and useful pyrotechnic device for exploding toy torpedoes and the like and has particular relation to a pistol-type torpedo shooter which consists in the combinations, constructions and arrangements herein described and claimed.

Generally, the invention consists in a device for firing of torpedoes which device is similar in general appearance to the automatic pistol, but which embodies distinct features not heretofore known in this art.

The primary object of the invention is to provide a device of this kind which will insure a maximum of safety and will at the same time provide a device which will be simple in its operation and be capable of being produced at very low cost.

It should be stated that any kind of ordinary toy torpedo may be utilized in the present invention, even those which do not embody the usual agglutinating material, such as wood flour, paper dust, confetti, etc., which improved torpedoes are considerably more costly than those not having these agglutinants.

While the primary object of the invention is to provide safety to the person firing the torpedo and bystanders, it is worthy of note that the device is also very well adapted to the testing of toy torpedoes at manufacturing plants, where, in the past, many workmen have been injured when testing such articles.

Other objects and advantages will appear in the following specification and the novel features of the device will be particularly pointed out in the appended claim.

The invention is illustrated in the accompanying drawings, forming part of this application, in which

Figure 1 is a side elevational view of the device, partly broken away;

Figure 2 is a longitudinal sectional view of the same;

Figure 3 is a similar view, partly in section showing the device in cocked position;

Figure 4 is an elevational view of a modified form of the device;

Figure 5 is a view similar to that shown in Figure 4, but partly in section in order to show the interior mechanism in cocked position;

Figure 6 is a view similar to Figure 5, but showing the device in its normal position, and

Figure 7 is a detail plan view of an operating part of the device.

Referring more particularly to the drawings, we have shown therein a torpedo-shooter having

a longitudinal tubular barrel 10 slidably mounted in an encircling handle or gripped portion 11 wherein is horizontally mounted a wire spring 12 which passes through an opening (not shown) in a catch member 13 slidably mounted in a guide member 14 which is permanently affixed to the barrel 10 as indicated at 15.

The spring 12 also passes through an opening (not shown) in one end of a bell crank type trigger 16 as indicated at 17, the trigger being pivoted upon a bearing 18 in the handle 11.

Within the barrel 10 is reciprocably mounted a rod 19 having at its forward end a hammer 20 and at its rear end a cocking handle 21. Permanently affixed to the rod 19 at a point intermediate its ends is a cylindrical latch member 22 having a circumferential groove 23.

The rear end of the barrel 10 is provided with a washer type bearing 24 and a similar member 25 is permanently affixed within the barrel at a point forwardly of the latch member 22. A coil spring 26 surrounds the rod 19 and bears against the rear of the hammer 20 and against the member 25 and normally tends to force the hammer 20 forwardly. A stop 27 is rigidly attached to the handle 11 and extends through a slot 28 cut in the barrel 10 and is normally in contact with the latch member 22. A firing chamber 30 is threaded upon the front end of the barrel 10 and is provided with a short downwardly extending nozzle 31 which is open at its bottom as indicated at 32.

The firing chamber 30 is provided with a heavy firing plate 32 at its front end.

The barrel has a loading opening cut in its top side as indicated at 33 and a small opening 34 is provided in the barrel at a point immediately forward of the member 25.

In operation, the grip 11 is held in one hand of the user and the cocking handle 21 is pulled rearwardly until the catch 13 engages the groove 23 of the latch member 22. As the handle 21 is drawn back, the hammer 20 will, of course, also be retracted and the spring 26 will be compressed between the hammer and the member 25 and the air in the barrel in the space first occupied by the spring will be released through the opening 34.

The grip 11 is then pushed forwardly to the position shown in Figure 3.

The device is now ready for loading and a torpedo is placed in the barrel through the opening 33 and the device is fired in the manner of the ordinary pistol, by pressing the trigger 16, which causes the spring 12 to move downwardly,

thus causing the downward movement of the catch 13 in the guide member 14, due to the downward distortion of the spring 12, which passes through the catch 13 as above described, 5 thus causing the release of the rod 19. By means of the energy stored in the spring 26 a violent forward movement of the hammer 20 immediately takes place, thus causing the torpedo to be impinged between the hammer and 10 the striking plate 32 and thus fired. The particles of gravel usually found in toy torpedoes will be forced to take a downward path through the opening 32. Any recoil will be taken up 15 functionally between the barrel 10 and the slideable grip 11 as the barrel is forced backwardly by the shock.

In the modified forms shown in Figures 4 to 7, the only material differences in construction are the provision of a pair of circumferential ridges 20 for limiting the sliding movement of the grip portion 36 and the modified form of trigger mechanism. The trigger mechanism consists of a vertical latch member 37 slidably mounted in the grip 36 and being pressed upwardly by a 25 coil spring 38. A pair of dogs 39 are preferably made integral with latch member 37 and the lower of these serves as a bearing or stop for the spring 38, the lower end of which spring bears against the interior of the grip 36 in any 30 well known manner. A trigger 40 is pivotally mounted within the grip 36 as indicated at 41 and has its other end forked as shown at 42 and slidably mounted between the dogs 39. The

operation of the modified form shown in Figures 4 to 7 will, of course, be identical with that of the form shown in Figures 1 to 3.

While the forms shown in the drawings are the preferred forms of our invention, it will be 5 apparent to those skilled in the art that the invention is not so limited but that various minor modifications and changes may be made therein without departing from the spirit of the invention or the scope of the appended claim. 10

We claim:

A torpedo-firing device consisting of a barrel having a firing chamber at the front end thereof and a downwardly pointing open nozzle in communication with the firing chamber, a firing 15 plate mounted at the front end of the firing chamber, a hammer slidably mounted in the barrel, a spring mounted in the barrel and adapted to urge the hammer into contact with the plate, a handle attached to the hammer and projecting rearwardly through the barrel, a latch mechanism for holding the hammer in retracted position, a hand grip slidably mounted on the barrel and a trigger actuated release for the latch mechanism mounted in the hand grip, 20 said release consisting of a detent for engaging the latch and slidably mounted upon a flexible wire carried by the hand grip in parallel relation to the barrel and a bell crank type trigger having one end attached to the wire. 30
